UNITED STATES PATENT OFFICE.

WILLIAM H. GROVER, OF MAUMEE, AND CLARENCE E. MERRITT AND WILLIAM S. POOLEY, OF TOLEDO, OHIO.

SIGNAL MEANS FOR ELEVATORS, ETC.

Application filed August 8, 1921. Serial No. 490,559.

This invention relates to signal systems and particularly to one for use in connection with a bank or battery of elevators to designate to the operator of each elevator when his car should arrive at, how long it should remain, and when it should leave successive points in a run and the direction it should travel.

In stores, office buildings and other buildings employing banks of elevators, it is customary to use what is known as the "manual system" of starting. With this system a starter stands on the main floor and dispatches the cars from such floor at certain intervals, and also in some cases, by the use of a system of buzzers, dispatches the car from the top floor on the down run. This starting system, especially where five or more elevators are employed, is inefficient and expensive in operation and the starter has no control over an operator between the starting floors. It is found that out of the different starting combinations in a bank of elevators, using the manual system of starting, the combination most efficient is to have part of the elevators going up while the others are doing down. A complete analysis of this arrangement of dispatch shows that on many floors, under ideal conditions, the traffic must frequently wait intervals that exceed 100 seconds, while at other times several cars will be found at a floor at once. This system of starting is also objectionable due to the waste energy required to stop and start the elevators and as most power is sold on a maximum demand basis, owners are paying a much higher maximum charge than is necessary.

The object of our starting means is to overcome the above and other objections incident to the starting systems heretofore used, by the provision of an automatic starting system which will successively indicate to each operator when his car should start from any floor whether up or down also when it should be at each succeeding floor during a complete round trip, so that an operator knows at any period in a trip where his car should be and which direction he should be going at such period, thus providing for a more efficient running of the elevators and insuring more

trips in a day and the carrying of a greater number of passengers than is possible with the starting systems heretofore used, of which we are aware.

The invention is fully described in the following specification, and while in its broader aspect it is capable of embodiment in numerous forms, a preferred embodiment thereof is illustrated in the accompanying drawings, in which,—

Figure 1 is a wiring diagram for a starting system embodying our invention, with two cars only shown in connection with the diagram. Fig. 2 is a similar diagram providing for two runs of different length for an elevator, the system being adapted for use in connection with either run. Fig. 3 is a plan view of the master switch and operating means therefor. Fig. 4 is a face view of an indicating dial of the system. Fig. 5 is a section thereof on the line 5—5 in Fig. 4, with parts separated and parts removed, and Fig. 6 is an elevation of the two bushing members secured within each indicating opening of the dial.

The signal system or means embodying the same consists essentially of three parts, a master switch, an indicator for each elevator of a set, and a connecting board.

The master switch in its preferred form comprises a commutating switch having a circular series of spaced contacts 10 of segmental form and insulated from each other, the signals being equi-distantly spaced and cooperating with the insulating spacing therebetween to form a commutating ring 11. A contact segment 10 is provided for each floor landing or elevator stop of the building, less 2, figuring both the up and down trips, so that if the building has nine floors or as in the case of the present illustration, eight floors and basement, sixteen segments are provided in the commutating ring. The reason that the number of segments do not correspond to the number of stops in a trip is that the first and last floors each answer for two stops, in other words, the first floor answers for the first stop on the up trip and the last stop on the down trip and the same with respect to the upper floor. This switch has a power shaft 12 disposed

centrally of its commutator ring and carrying an arm 13 for revoluble movements therewith and provided at its outer end with a brush or contact 14 for riding on the contact segments 10 when the arm is revolved. A circuit ring 15 is provided for the switch in concentric relation to the shaft 12 and a contact 16 on the arm 13 continually rides on the ring and is in closed circuit with the brush 14 through a wire or other suitable electrical connection 17. The brush 14 is adapted to remain in contact with each segment until after contact has been made with the succeeding segment. The shaft 12 is connected by a train of reducing gears 18 to the shaft of a motor 19 or other suitable source of power and is operated at any desired speed independently of the speed of operation of the elevators.

The indicating dial or element of the apparatus is provided with as many signal devices in the present instance, electric lamps, as there are stops for the elevator, or in other words, as there are segments 10 in the switch, and these lights or signaling devices may have any desired arrangement, being shown in the present instance, as circularly arranged. One of these indicators is disposed in each car of the set in convenient view of the operator.

The indicator employed in the present instance comprises a circular base member 20 having a circular series of openings 21 therein for receiving respective sockets 22 for electric lamps 23, and a top plate 24 sets over the base plate 20 and is provided therethrough with openings or windows 25 in register with the openings 21 of the base plate and for receiving the outer end portions of the lamps 23. Each opening 25 is provided with a transparent member 26 without the lamp 23 and provided with a numeral or designation indicating a particular floor or stop of the elevator, the stops in the illustration running from the basement floor up to the eighth floor and then down to the basement, as shown in Fig. 4. The transparent members 26 are held in position within the openings 25 by inner and outer bushing members 27 and 28 respectively, the latter being of a size to closely fit the opening and the former being longitudinally split and normally of a size larger than the opening, to require a compression of the bushing before being inserted in the opening. It is preferable to have either the transparent members 26 or the lamps 23 of white for the stops indicated during an upward run of an elevator, and to have the transparent members 26 or lamps 23 red for the stops indicated during a down trip of an elevator, thus establishing the element of direction at all times.

A connecting board is interposed between the indicator elements and the master switch and has as many connecting blocks 29 as there are commutating segments 10 in the

master switch, and each block is provided with as many connections as there are cars in the system. For instance, if there are seven cars in the system, each block will have provision for seven connections 30 as shown, with each connection of a block in circuit with a certain commutating segment 10 of the switch and with a different signal lamp of each of the several elevators of the system. Each block has a designation at its inner end corresponding with the designation of the commutating segment 10 with which it is connected by a respective wire 31, and each different connection 30 of a block has connection with a respective lamp of each indicator through a wire 32. The other side of each lamp of each indicator is in connection through a common wiring 33 with a battery line 34 leading to one side of a battery 35 or other source of electrical energy supply. The other side of the battery is connected by a lead 36 to the circuit ring 15 of the master switch. The connections 30 of some of the blocks 29 have reference letters at the sides thereof indicating the respective cars with which the connections are associated. Some of the cars and the wiring are omitted from the diagram, however, in order to avoid confusion.

In the operation of the signal system embodying the invention it is only necessary to close the battery circuit and start the motor 19 or other means which drives the timing arm 13 of the switch. If the arm 13 is in position for its brush 14 to have contact with the commutating signal B of the master switch, the battery circuit to the connecting block B will be closed and the connections in turn from such block to the respective lamps or indicator means of the different cars of the bank will also be closed. If the arrangement is such that the cars should be approximately two floors apart during a run, the car A will have its basement light on, the car B will have its second floor light on, the car C will have its 4th floor light on, the car D will have its 6th floor light on, and so on throughout all of the elevators of the bank, thereby indicating to the operator in each elevator where his car should be when the commutating segment B of the switch is in closed circuit. As the brush passes from the contact segment B to the segment 1, the indicator lights of the different elevators in circuit in segment B will go out and the next light in order on each elevator should then be on, by reason of the switch segment 1 being disposed in the closed circuit, and indicate that each elevator should be at or start for the next stop. It is preferable that the brush 14 will remain in contact with each segment until after it has made contact with the next segment in order, as this facilitates the running of the car by the operator, for after making a stop he can remain at such stop until the light for the next stop

comes on which is the signal to leave the floor at which stopping and proceed to the next floor. As the switch arm 13 continues its revolution the indicating of the stops for each elevator in the bank is automatically effected so that each operator can at all times tell where his car should be at any period in a run and can therefore gauge the running of his elevator accordingly, so that his stops will correspond as nearly as possible to the stops indicated by the indicator in his car. It will be understood that if desired each elevator of a bank may be provided with an individual switch and in some cases this is found desirable.

It is evident that the signal system may be regulated to cause a faster or slower running of the elevators as may be desired, the change of speed being accomplished by changing the speed of revolution of the switch arm 13.

It is found in practice that with this system cars will not lap or run ahead of schedule time during runs; that a more uniform and efficient running of all of the cars of a bank is effected, and that more trips and the carrying of a greater number of passengers in a day is accomplished, and in addition the service of a starter is eliminated. It also prevents all cars either going up or coming down at the same time.

In some buildings it is desired at certain times of a day to cut out the top floor or several top floors, as for instance, where a restaurant or dining room is located on the top floor of the building and patrons are therefore traveling to and from such floor only during meal hours. In such case the commutating switch of the signal means may have two sets of contact segments, one including the segments for all of the floors and the other excluding the segments for the floors to be cut out. A wiring diagram of a signal means including this changeable feature in association with one indicator unit is illustrated in Fig. 2. In this figure the outer set of segments corresponds in number to the full number of stops or floors for an elevator and the inner set of segments corresponds in number to the reduced number of floors or stops for an elevator. The segments of both sets are wired in the same manner to the indicator means as hereinbefore described, except that the indicators for the floors adapted to be cut out are in connection only with the extra segments of the outer set. In the diagram shown in Fig. 2, 40 designates the revoluble arm of the master switch, which arm carries two brushes 41 and 42, respectively, in engagement with outer and inner commutating rings 43 and 44, the segment of the outer ring being provided for the greater number of stops and those of the inner ring for the lesser number of stops. The brushes 41 and 42 are in electrical connection, respectively, with circuit

rings 45 and 46. The circuit ring 45 is connected to a battery or source of electrical energy supply 47 through a wire 48, the other side of the battery being in connection through a wire 49 and switch 50 with the sides 70 of the elevator signal devices 51 which are in common circuit. The other side of each signal device 51 is connected to respective segments of the commutating rings 43 and 44, the signal devices for the floors adapted to be cut out having connection alone with the extra segments of the commutating ring 43. The other circuit ring 46 is in connection through a wire 52 with a battery or source of electrical energy supply 53, which is connected by a wire 54 and the switch 50 to the common side of the signal devices 51. The switch 50 is common to both battery circuits and when moved to close one circuit opens the other.

We wish it understood that our invention is not limited to any specific construction, arrangement or form of the parts, as it is capable of embodiment in numerous forms without departing from the spirit of the claims.

Having thus described our invention, what we claim as new and desire to secure by Letters Patent, is,—

1. In a signal apparatus, a commutator having a single row of segments, a switch arm therefor, a branch block having a plurality of connected contacts, the contacts in each block being connected to a different contact on the commutator, a plurality of 100 elevator cars, a plurality of signals on each car distinctive to each floor, and means for connecting one signal in each car to a contact on the same branch block.

2. In a signal apparatus, a commutator having a single row of segments, a switch arm therefor, a branch block having a plurality of connected contacts, the contacts in each block being connected to a different contact on the commutator, a plurality of 110 elevator cars, a plurality of signals on each car distinctive to each floor, and a removable connection between said signals and branch block.

3. In an elevator signal apparatus, a bank 115 of elevators each operating to stop at a plurality of floors at each of its up and down trips, signalling means carried by each elevator including a signal for each of said floors for both the up and down trips, circuits for each of the signalling means and the signals thereof, switching means including a plurality of segments one for each of the floors of both the up and down trips, and an arm engageable with the segments, a 120 connecting board comprising a plurality of branch blocks each including a plurality of connected contacts, the contacts of each group being connected to a different segment of said switching means for permitting the selective 125 connection of the signals to the segments.

connection of any of the contact blocks to any of the signals on the elevators in predetermined order, and means for effecting uniform drive of the arm of the switching means.

4. In an elevator signal apparatus, a bank of elevators each operating to stop at a plurality of floors at each of its up and down trips, signalling means carried by each elevator including a signal for each of said floors for both the up and down trips, circuits for each of the signalling means and the signals thereof, switching means including a plurality of segments, one for each of the floors of both the up and down trips, and an arm engageable with the segments, a connecting board comprising a contact member for each segment, a plurality of branch blocks each including a plurality of connected contacts, the contacts of each group being connected to a different segment of said switching means for permitting the selective connection of any of the contact members to any of the signals on the elevators in predetermined or-

der, and means for effecting uniform drive 25 of the arm of the switching means.

5. In an elevator signal apparatus, a bank of elevators each operating to stop at a plurality of floors during both its up and down travel, signalling means carried by each elevator and including a signal for each floor for both the up and down travel, indicating the time at which the elevator should arrive at the respective floor, circuits for the respective signals, switch means for controlling the various signals, and means comprising branch blocks and connections for the circuits which may be selectively arranged to cut in or out the signals for one or more of said elevators and to redistribute the 40 signals for the elevators which it is then desired to operate.

In testimony whereof, we have hereunto signed our names to this specification.

WILLIAM H. GROVER.
